UNITED STATES PATENT OFFICE.

JOSEPH L. FIRM, OF BERWYN, ILLINOIS, ASSIGNEE TO THE GOSS PRINTING PRESS COMPANY, OF CHICAGO, ILLINOIS, A CORPORATION OF ILLINOIS.

PRINTING-PRESS.

1,025,257.

Specification of Letters Patent.

Patented May 7, 1912.

Application filed January 3, 1911. Serial No. 600,425.

To all whom it may concern:

Be it known that I, JOSEPH L. FIRM, a citizen of the United States, and a resident of the city of Berwyn, county of Cook, and 5 State of Illinois, have invented certain new and useful Improvements in Printing-Presses, of which the following is a specification.

This invention relates to improvements in 10 printing presses and more specifically to that class thereof designed for multi-color printing.

The object of this invention is the production of a printing press of the character 15 mentioned which will be so designed that the plates or forms carried by the form cylinders included in the construction may be readily and quickly removed therefrom or the same may be readily accessible for cleaning without necessitating disturbance of the 20 inking cylinders.

A further object is the provision of a printing press as mentioned by means of which a plurality of colors may be offset or 25 applied to the web at one operation; and a further object is the provision of a press which will be of economical construction and efficient in operation.

Other objects will appear hereinafter.

30 With these objects in view my invention consists in the combinations and arrangements of parts hereinafter described and claimed.

My invention will be best understood by 35 reference to the accompanying drawings forming a part of this specification and in which—

Figure 1 is a side elevation of a printing press embodying the invention, and Fig. 2 40 is a diagrammatic view thereof in longitudinal section.

The preferred form of this invention as 45 illustrated in the drawings comprises a supporting frame 1 in which is rotatably mounted substantially centrally therein a transversely extending shaft 2. Mounted upon said shaft, the same being fixed thereto is a form cylinder 3 upon which are arranged forms or plates 4, 4', 4'', 4''' secured thereto in the ordinary manner, each set of said forms or plates being adapted to receive a color different from that received by the others, and each color is applied by the inking cylinders about to be described.

55 Rotatably mounted in the frame 1 at one

end thereof and parallel with the shaft 2 is a shaft 5 to the respective ends of which are secured rings or annular supporting members 6, said members 6 being of substantially the same diameter as that of the cylinder 3. Extending between and having their extremities rotatably mounted in the supporting members 6 adjacent the peripheries thereof is a plurality of spaced inking cylinders divided preferably into four sets each 60 set comprising four cylinders, said cylinders being designated as 7, 7', 7'', 7''''. Adjacent inking cylinders in each set contact with ink distributing cylinders 8 which have their extremities also rotatably mounted in the 65 supporting members 6, said cylinders 8 being preferably so arranged as to be adapted when the device is in operation in addition to being rotated to be reciprocated longitudinally in order to effect a more thorough 70 and uniform distribution of the ink delivered thereto upon the inking cylinders contacting therewith. Fixed to one end of the cylinder 3 is a gear 9 which is operatively connected with a similar gear 10 fixed to the 75 shaft 5 by means of a pinion 11. The arrangement is such that when in operation, the cylinder 3 will rotate in the same direction as that in which the inking cylinders 85 revolve so that their contacting surfaces will pass in opposite directions. Said inking cylinders are so arranged that when the same are revolved as above mentioned, they 80 will contact the periphery of the cylinder 3, each set thereof contacting a portion of the 85 periphery of said cylinder not contacted by the other sets; the cylinders 7 being arranged to contact only with the plates or forms 4, the cylinder 7' with the forms or plates 4', the cylinders 7'' with the forms 90 or plates 4'', and the cylinders 7''' with the forms or plates 4''''. Arranged about the 95 shaft 5 are ink fountains 12, 13, 14 and 15, the extremities thereof being fixed to the frame 1 so that when the device is in operation 100 said fountains remain stationary. Arranged in said ink fountains are fountain rollers 16. Arranged at the extremities of said ink fountains and fulcrumed at 17 are bell-crank levers 18, said levers carrying 105 rollers 19, 19', 19'', and 19''' at their outer extremities, said rollers 19 being adapted to contact with the ink distributing cylinders 8 and the fountain rollers 16 in order to 110 effect the transfer of ink from the latter to

2
 said distributing cylinders. The arrangement is such, however, that each of said movable fountain rollers will be adapted, when the device is in operation, to contact 5 the ink distributing cylinders 8 of a set of inking cylinders not contacted by the others, the roller 19 being adapted to contact and deliver ink only to the distributing cylinders 8 coöperating with the inking cylinders 7, 10 the roller 19 being adapted to contact only with the ink distributing cylinders 8 coöperating with the inking cylinders 7', the fountain roller 19" with the ink distributing cylinders 8 coöperating with the inking cylinders 7", and the fountain roller 19''' only with the ink distributing cylinders 8 coöperating with the inking cylinders 7'''. The rocking or oscillation of said movable inking rollers to effect this contact with the 15 ink distributing cylinders 8 is effected by means of a series of cams 21 which coöperate with the rollers 20 of the levers 18, this construction being illustrated and described in my co-pending application, Serial No. 25 600,424 filed January 3rd, 1911. Hence further detailed description here is not necessary since reference to said application may be made if such detailed description is desired. With the arrangement above de- 20 scribed then it will be seen that if different colors are contained in the various fountains 12, 13, 14, and 15 different colors will correspondingly be applied to the plates or forms 4, 4', 4'', and 4''' respectively upon the form 25 cylinder 3.

Rotatably mounted in the frame 1 at the opposite side of the form cylinder 3 is an offset cylinder 22, the same being preferably provided with a rubber coat or covering 23 40 in order to facilitate the offsetting or transferring of the ink applied thereto to the web which is brought in contact with the periphery thereof. The offset cylinder 22 remains in constant contact with the form cylinder 3, the 45 periphery of said form cylinder being to the periphery of said offset cylinder directly as the number of sets of plates carried by said form cylinder or the number of sets of inking cylinders coöperating therewith; so that 50 in the present case the periphery of the cylinder 22 will be one fourth that of the cylinder 3. With this arrangement it will be seen that the different colors carried by the sets of forms or plates as applied thereto by 55 the inking cylinders will be applied upon the periphery of said offset cylinder one directly upon the other.

Rotatably and revolvably mounted in the frame 1 adjacent the offset cylinder 22 is an 60 impression cylinder 24, and arranged below said impression cylinder 24 is a second impression cylinder 25 which coöperates with a form cylinder 26, the latter being adapted to apply a single color to the opposite side 65 of the web to that to which the multi-colors

are applied. The web 27 fed to the impression cylinder 24 is engaged by gripping devices 28 of any approved construction, gripping devices as shown and described in my Letters Patent, No. 366,388 granted July 12th, 1887 being preferably employed. Said gripping devices 28 are adapted to carry the extremity of the web engaged thereby to the point of tangency with the cylinder 25 whereupon the same releases said extremity 70 of said web to permit of the same being engaged by the gripping devices 28' arranged in the periphery of said cylinder 25. The cylinders 24 and 25 are operatively connected by meshing gears 29 and 30 which are secured respectively thereto so that the same, when operating, will rotate at the same peripheral speed. The extremities of the shaft of the cylinder 24 are mounted in bell crank levers 31 at the vertices thereof, said levers 31 being arranged at the opposite sides of the frame 1, the lower extremities thereof being fulcrumed to the extremities of the shaft of the cylinder 25. The opposite extremities of said levers 31 are provided with 80 rollers 32 which engage cam grooves 33 formed in the outer sides of cam members 34 fixed to the respective extremities of the shaft 2. The cam grooves 33 are so designed that upon each rotation of the cylinder 3, 95 the impression cylinder 24 will be rocked into engagement with the offset cylinder 22 remaining in engagement therewith through one complete rotation thereof. With this arrangement then it will be seen that the cylinder 24 will be rocked into engagement with the cylinder 22 once in every four rotations of the latter, in other words after four coats of color have been applied to said offset cylinder the web carried by the cylinder 105 24 will be brought into contact with said offset cylinder effecting the transferring or offset with the four colors carried by said offset cylinder is one rotation thereof or in one operation.

Cylinders 24, 25 and 26 are driven intermittently and a sheet of paper cut from web 27 is delivered to cylinders 24 and 25 at the proper time as will be readily understood by those skilled in the art. Any suitable means 115 may be employed for this purpose and no claim is made herein to any specific means for cutting and feeding the paper sheets to cylinders 24 and 25.

In operation, the impression cylinder 24 together with the parts operatively connected therewith will be intermittently operated, the duration of the period of operation of said cylinder and parts connected therewith being to the duration of the period of 120 inoperativeness directly as the periphery of the cylinder 22 is to the periphery of the cylinder 3, in other words, the cylinder 24 will be turned through one complete rotation every fourth rotation of the cylinder 22, 130

the period of operation occurring when the cylinder 24 is rocked into contact with said cylinder 22 by means of the lever 31 as previously described. Hence, in operation, 5 after the four colors have been applied to the offset cylinder 22 as above described, the web will be pressed into engagement therewith to effect the offsetting or transferring of the colors from the cylinder 22 in one 10 operation. In order to facilitate the transfer of the color or ink from the cylinder 22 to the web, a water applying mechanism 50 is preferably provided. Said water applying mechanism is so arranged that once 15 every four rotations of said cylinder 22, water will be applied to the periphery thereof, the application of water to said cylinder occurring during the interim between the transfer of the ink from the periphery of 20 said cylinder 22 to the web and the application of a new coat of color or ink to said cylinder. By first applying a coat of water to the periphery of said cylinder the ink or color applied thereto will adhere thereto 25 with less tenacity so that when the web is brought into contact with said cylinder the ink or color carried thereby will be readily and completely removed.

Any suitable means may be employed for 30 operating water applying mechanism 50. The construction shown comprises a reciprocating rod 52 carrying at one end a cam roller 53 operating in cam slot 33 and having its other end connected with one arm of a 35 bell crank lever 54. The other arm of bell crank 54 is connected by means of a link 55 with a lever 56 arranged to operate the water applying mechanism 50 at the proper time.

Arranged adjacent the form cylinder 3 40 is a water applying mechanism 51, said mechanism being provided in order to adapt the machine for employment in lithographing as will be readily understood.

With a printing press of a construction 45 as above set forth the inking rollers being separated from or positioned laterally of the form cylinder, the plates carried by the latter may be readily and quickly removed or replaced, or cleaned if desired without 50 necessitating the disturbance of said inking rollers such as is now necessary in machines now generally in use in order that access to the plates arranged upon the form roller therein may be gained. By the introduction 55 of an offset cylinder a plurality of colors may be applied to the web at a single operation. Further, the press is durable and economical, and the same is not susceptible to readily becoming inoperative. By the construction as set forth it will be seen that 60 in operation the primary colors will be first applied by the form cylinder to the offset cylinder and that the secondary colors will be applied thereover, so that, when all of 65 the colors are offset on to the web, the sec-

ondary colors will be underneath and the primary colors thereover or on top, thus reversing the order now universally in vogue of removing the colors from the form cylinder. 70

While I have shown what I deem to be the preferred form of my invention I do not wish to be limited thereto as there might be various changes made in the details of construction and the arrangements of parts described without departing from the spirit of the invention as comprehended within the scope of the appended claims. 75

Having described my invention what I claim as new and desire to secure by Letters Patent is:

1. In a printing press, the combination of a form cylinder; a plurality of sets of rotatably and revolvably mounted inking cylinders adapted each to contact a portion of the periphery of said form cylinder not contacted by the others; an impression cylinder; and an offset cylinder interposed between said impression cylinder and said form cylinder, substantially as described. 85 90

2. In a printing press, the combination of a form cylinder; a plurality of sets of rotatably and revolvably mounted inking cylinders, each set of said cylinders being adapted to contact a portion of the periphery of said form cylinder not contacted by the others; an impression cylinder; and an offset cylinder interposed between said impression cylinder and said form cylinder, 100 the periphery of said form cylinder being to the periphery of said offset cylinder directly as the number of sets of inking cylinders coöperating with said form cylinder, substantially as described. 95

3. In a printing press, the combination of a form cylinder; a plurality of sets of rotatably and revolvably mounted inking cylinders, each set of said cylinders being adapted to contact a portion of the periphery of said form cylinder not contacted by the others; an offset cylinder contacting said form cylinder, the periphery of said form cylinder being to the periphery of said offset cylinder directly as the number of sets of inking cylinders coöperating with said form cylinder; and an impression cylinder adapted to intermittently contact said offset cylinder, substantially as described. 110 115

4. In a printing press, the combination of a form cylinder; a plurality of sets of rotatably and revolvably mounted inking cylinders, each set of said cylinders being adapted to contact a portion of the periphery of said form cylinder not contacted by the others; an offset cylinder contacting said form cylinder, the periphery of said form cylinder being to the periphery of said offset cylinder directly as the number of sets of inking cylinders coöperating with said form cylinder; and an impression cylinder 120 125 130

adapted to intermittently contact said offset cylinder, the duration of the intervals of non-contact being to the duration of the intervals of contact of said impression cylinder with said offset cylinder directly as the periphery of said form cylinder is to the periphery of said offset cylinder, substantially as described.

5. In a printing press, the combination of
10 a rotatable form cylinder; a plurality of sets of rotatably and revolvably mounted inking cylinders, each set of said cylinders being adapted to contact a portion of the periphery of said form cylinder not contacted
15 by the others; ink fountains; ductor rollers adapted to transfer ink from said fountain to said inking cylinders; means whereby each of said ductor rollers will, upon revolution of said inking cylinders, contact a
20 set of inking cylinders not contacted by the others; an offset cylinder contacting said form cylinder, the periphery of said form cylinder being to the periphery of said offset cylinder directly as the number of sets

of inking cylinders coöperating with said form cylinders; and an impression cylinder adapted to intermittently contact said offset cylinder, substantially as described.

6. In a printing press the combination of
a rotatable form cylinder; a plurality of rotatably and revolvably mounted inking cylinders arranged in cylindrical conformation laterally of and parallel with said form cylinder, said inking cylinders being adapted to successively contact with one set of
30 said form cylinders with the latter is rotated and said inking cylinders are revolved; an offset cylinder contacting said form cylinder; and an impression cylinder
35 adapted to contact said offset cylinder, substantially as described.

In testimony whereof I have signed my name to this specification in the presence of two subscribing witnesses.

JOSEPH L. FIRM.
